HATCH COVER FOR RAILWAY CARS

John L. Carney, Jr., St. Louis, and Bernard A. Trompeter, O'Fallon, Mo., assignors to ACF Industries Incorporated, New York, N.Y., a corporation of New Jersey

Filed June 19, 1963, Ser. No. 289,005

12 Claims. (Cl. 105—377)

This invention relates to hatch covers for openings in the roofs of railway cars and particularly to such hatch covers which are moved toward and away from elongate hatch openings in a direction generally transversely of the car.

Among the several objects of the present invention may be noted the provision of a hatch cover and associated hatch opening which will permit the loading of a railway car in a continuous uninterrupted operation without the shut-off or stopping of the loading means until the car is filled or loaded; the provision of such a hatch cover and associated hatch opening in which the hatch opening may be easily uncovered and the car filled in a manner to utilize the maximum amount of space within the car and to minimize pyramiding of the loaded material; the provision of such a hatch cover which may be moved transversely of the car between open and closed positions with a minimum of force being applied to the hatch cover; and the provision of such a hatch cover and associated opening which is simple in operation and economical in construction.

In general, the above objects are accomplished by an elongate hatch cover positioned over an elongate hatch opening in the roof of a railway car and mounted in guideways extending generally transversely of the car for movement between open and closed positions relative to the hatch opening. More specifically, anti-friction means secured to the hatch cover move back and forth in the guideways when the hatch cover is opened and closed, thereby to permit such opening and closing with a minimum of effort. Other objects of this invention may be in part apparent and in part pointed out hereinafter.

The invention accordingly comprises the constructions hereinafter described, the scope of the invention being indicated in the following claims.

In the accompanying drawings, in which several possible embodiments of the invention are illustrated,

FIGURE 1 is a perspective view of a railway car in accordance with one embodiment of this invention, a plurality of elongate hatch covers being mounted over a plurality of elongate hatch openings spaced longitudinally along the roof of a hopper car;

FIGURE 2 is a partial plan of the railway car of FIGURE 1, an intermediate hatch cover being shown in open position permitting access to the hatch opening;

FIGURE 3 is an enlarged transverse section taken generally along line 3—3 of FIGURE 2, the broken line positions of the hatch cover illustrating intermediate and end positions thereof;

FIGURE 4 is an enlarged section taken generally along line 4—4 of FIGURE 3 and showing guide means for the hatch cover;

FIGURE 5 is an enlarged fragmentary view of a means to hold the hatch cover in closed position over the hatch opening;

FIGURE 6 is a further embodiment of this invention in which a removable stop is illustrated for stopping and retaining the hatch cover in its fully open position; and

FIGURE 7 is a plan of an additional embodiment of this invention in which a single elongate hatch cover is illustrated extending substantially the length of the car.

Referring now to the drawings, a hopper car generally designated C has a tubular tank-shaped body B supported

adjacent each end on trucks T. Body B comprises a cylindrical tank shell L supported on side sills S. Shell L acts as a longitudinal beam and eliminates the necessity of a center sill, thereby to provide a smooth clean bore interior within shell L for facilitating the unloading and cleaning of the hopper car. It is to be understood that suitable bottom discharge openings (not shown) are provided for unloading the contents of the car.

Referring particularly to FIGURES 2 and 3, the roof of the hopper car is indicated at 10. Bulkheads or transverse partitions 12 separate the car into separate compartments and each compartment has a separate elongate hatch opening 14 through the roof of the car and arranged centrally of the width of the car. Surrounding the hatch openings 14 and mounted on roof 10 is a horizontal platform 16 forming a running board for the car. Platform 16 has a rectangular opening 18 extending longitudinally along the roof of the car to permit access to hatch openings 14. Supporting platform 16 are struts 20 welded to shell L at their lower ends.

Surrounding each hatch opening 14 along its perimeter is a frame 22 welded to the adjacent edge 24 of shell L which defines hatch opening 14. Each hatch frame 22 extends upwardly from its respective opening 14 and has an outturned curved upper flange 26 forming a substantially horizontal seat for a hatch cover generally designated 28. An intermediate hatch cover 28 and associated hatch opening 14 are of a length greater than the length of end hatch covers 28 and associated hatch openings 14. Each hatch cover 28 and associated opening 14 is elongate in shape and is substantially identical except for dimensions.

Each hatch cover 28 comprises a generally flat body plate 30 having an integral downturned circumferential flange 32. A resilient gasket 34 is secured to the underside of plate 30 and is adapted to seat in sealing relation on flange 26 when the hatch cover is closed. Mounted at intervals along the length of each hatch cover 28 are downwardly opening channels 36 constituting cover supports extending transversely of the car as well as stiffeners for the hatch cover. The outer ends of channels 36 are slotted at 37 (FIGURE 3). Clip angles 38 (see FIGURE 4) connect roller brackets or arms 40 to channels 36. Roller arms 40 extend outwardly from each channel 36 and downwardly from the adjacent flange 32 of hatch cover 28.

Mounted on a roller axle 41 fixed through the extending end of each roller arm 40 is a pair of upper rollers 42, one on each side of roller arm 40 (see FIGURE 4). A roller axle 44 fixed through the extending end of each arm 40 mounts a second pair of lower rollers 46, one on each side of roller arm 40. A box channel 48 is mounted on a pair of inner struts 50 and a pair of outer struts 52 (see also FIGURE 3). Suitable clip angles connect struts 50, 52 to platform 16. A horizontal support angle 56 extends longitudinally of the car and is suitably secured, such as for example by welding, to shell L. Outer struts 52 are secured at their lower ends to support angle 56. It is noted that the upper surface of platform 16 and the upper surface of channels 48 are in substantially the same horizontal plane.

A slot 58 extends longitudinally along the upper side of box channel 48 and receives roller arm 40 for back and forth movement upon the opening and closing of hatch cover 28. The dimensions of box channel 48 are such that the distance between the upper and lower inner surfaces are sufficiently greater than the diameter of rollers 42 and 46 to permit rollers 42 to contact the upper inner surface and rollers 46 to contact the lower inner surface, the hatch cover 28 clearing hatch frame 22 as indicated by the intermediate broken line position of hatch cover

28 illustrated in FIGURE 3 when rollers 42 and 46 are so positioned and the cover is moved between open and closed positions. This arrangement allows hatch cover 28 to be supported by rollers 42, 46 within box channels 48 during movement between open and closed positions, channels 48 constituting guideways for the hatch cover. A downturned flange 60 at the outer end of each channel 48 constitutes a stop for rollers 42 as illustrated by the outer broken line position of hatch cover 28 in FIGURE 3, rollers 42 abutting flange 60 in the fully opened position of the hatch cover. Retaining hatch cover 28 in its outer end position against stop 60 is a slot or recess 61 receiving rollers 42. Rollers 42 are easily removed from recess 61 by a slight upward tilting of the hatch cover. For removal of hatch cover 28, an outer end portion of the lower side of channel 48 is cut away as indicated at 62. Upon tilting of hatch cover 28 upwardly rollers 42 and 46 will drop out of cutaway portions 62. At the inner end of each channel 48, a recess 64 receives rollers 42 as illustrated in the solid line position of hatch cover 28 in FIGURE 3. This permits the hatch cover to tilt downward to seat on hatch frame 22. Box channels 48 and roller arm assemblies (formed by roller arm 40 and rollers 42, 46) constitute guideways and associated guides for the hatch cover.

For securing hatch cover 28 in closed position, hand wheels 66 are spaced at intervals along the length of each cover 28. Each hand wheel has a hub 68 internally threaded and receiving an externally threaded swing bolt 70. The lower end of bolt 70 is bifurcated to form yoke arms 72. Bracket 74 secured to the car fits between arms 72 and a bolt 76 extending through suitable openings mounts swing bolt 70 for pivotal swinging movement toward and away from hatch cover 28. Slot 37 in channel 36 is adapted to receive bolt 70 in the secured position of the hatch cover with hand wheel 66 drawn tight against the upper surface of the associated channel 36.

The operation is as follows: Beginning with the hatch cover in closed position, hand wheels 66 are loosened and swing along with swing bolts 70 away from the hatch cover as indicated in broken lines in FIGURE 3. Then, the hatch cover is lifted or tilted slightly from the edge adjacent the hand wheels to remove rollers 42 from recesses 64. In this position, the hatch cover is pushed transversely of the car to move rollers 42, 46 along the guideways formed by box channels 48. When stop 60 is engaged by rollers 42, the hatch cover is in its fully opened position, rollers 42 being received in recesses 61. To return hatch cover 28 to closed position, the cover is tilted slightly to remove rollers 42 from slots 61, then the cover is pulled transversely of the car until rollers 42 are received by recesses 64 permitting hatch cover 28 to tilt downward into engagement with hatch frame 22. Swing bolts 70 are next moved within slots 37 and hand wheels 66 are drawn tight against channels 36 to secure the hatch cover. It is to be understood that the number of hand wheels will normally depend on the length of the cover. While the hatch cover is illustrated on a hopper car, it may be employed on any desired type of freight car having a roof and hatch opening for loading the car. Also, it is to be understood that two hatch covers may be employed side-by-side, such as might be desirable if a partition extends longitudinally of the railway car.

Referring to FIGURE 6, an embodiment of this invention is shown in which a box channel 48A has a bolt 76 extending between opposite sides thereof and forming a stop for rollers 42 and the hatch cover. Bolt 76 may be removed from channel 48A to permit the hatch cover to be easily removed from the car.

Referring to FIGURE 7, a single elongate hatch cover 28A on a railway car is illustrated as an embodiment of this invention and extends substantially the length of the car. Hatch cover 28A is mounted similarly to hatch covers 28 illustrated in FIGURES 1-5. It is to be under-

stood that any desired number of hatch covers may be positioned along the length of the railway car.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

We claim:

1. In a railway hopper car, a roof covering the hopper car, an elongated hatch opening extending lengthwise longitudinally of the car, a hatch frame surrounding the hatch opening, an elongate hatch cover over the hatch opening slideable transversely of the car between open and closed positions, said hatch cover being seated on the hatch frame in the closed position and being removed from the hatch opening in the open position to permit access to the hatch opening, an arm secured adjacent one side of the elongate hatch cover and extending laterally from the hatch cover over the adjacent roof transversely of the car, a guideway mounted on the roof and extending transversely of the car generally parallel to the longitudinal axis of the arm, anti-friction means on the extending end of the arm engaging the guideway for sliding movement back and forth transversely of the car upon opening and closing of the cover, and releasable means to secure the hatch cover in closed position onto the hatch frame and to release the hatch cover from the hatch frame for sliding movement transversely of the car.

2. In a railway car as set forth in claim 1, said guideway comprising a box-shaped channel member having an upwardly opening slot receiving the arm for movement of the hatch cover back and forth, the anti-friction means on the extending end of the arm comprising a roller fitting within the box-shaped channel.

3. In a railway hopper car, a roof covering the hopper car, an elongate hatch opening extending lengthwise longitudinally of the car, an elongate hatch cover over the hatch opening slideable transversely of the car between open and closed positions, guide means secured to one side of the elongate hatch cover extending outwardly and downwardly from said one side, a support for the guide means secured to the roof and extending transversely of the car, and releasable means to secure the hatch cover in closed position and to release the hatch cover for sliding movement along the support transversely of the car to open position, the support mounting the guide means and hatch cover for back and forth sliding movement transversely of the car.

4. In a railway hopper car as set forth in claim 3, said guide means comprising an arm secured to the hatch cover and at least one roller mounted for rotation on the extending end of said arm, said support comprising a box-shaped channel extending transversely of the car and having an upper slot therein receiving the arm, the roller fitting within the channel for rotation upon back and forth movement of the hatch cover between open and closed positions.

5. A railway hopper car having a roof covering the hopper car, an elongate hatch opening extending lengthwise longitudinally of the car, a hatch frame surrounding the hatch opening, an elongate hatch cover over the hatch opening having at least a pair of arms extending outwardly and downwardly from one side thereof, a pair of rollers mounted on each of the arms and offset from each other, a guideway for the rollers secured to the roof and receiving the rollers for movement back and forth transversely of the car, said guideway having an upper roller support surface and a lower roller support surface, one of the rollers contacting the upper support surface and the other roller contacting the lower support surface for supporting the hatch cover when moved between open and closed position, the cover being cantilevered from the arms and biasing the rollers into engagement with the respective

support surfaces upon movement between opened and closed positions relative to the hatch opening, and releasable means adjacent the other opposite side of the cover to secure the cover in closed position.

6. The railway hopper car as defined in claim 5 wherein in a stop adjacent each end of the guideway limits the movement of the cover transversely of the car.

7. The railway hopper car as defined in claim 5 wherein said hatch cover has an outwardly opening slot on the side thereof opposite said one side, the releasable means being a swing bolt pivotally mounted adjacent the opposite side of the cover for movement between a position received within the slot and a position removed from the slot, an end of the bolt projecting from the cover when the bolt is received within the slot, and means on the projecting end of the bolt adapted to be drawn tight against the adjacent surface of the hatch cover when the bolt is within the slot thereby to secure the hatch cover in a closed position.

8. The railway hopper car as defined in claim 5 wherein means are disposed at the opened position of the hatch cover and at the closed position of the hatch cover to retain the hatch cover in such positions, the hatch cover being removed from the opened and closed retained positions thereof by tilting in a generally vertical plane extending transversely of the car.

9. A railway hopper car having a roof covering the hopper car, an elongate hatch opening extending lengthwise longitudinally of the car for substantially the entire length thereof, a hatch frame surrounding the hatch opening, an elongate hatch cover over the hatch opening and adapted to be seated on the hatch frame in a closed position, at least a pair of roller arms secured to one side of the hatch cover, a pair of rollers mounted on each of the arms and being offset from each other, a generally box-shaped channel adjacent each arm extending transversely of the car and in transverse alignment with the associated arm for receiving the rollers, each box-shaped channel being slotted to receive the associated arm, one of the rollers engaging the bottom of the channel and the other roller engaging the top of the channel for supporting the cover for back and forth movement, a stop adjacent each end of each channel to limit the movement of the rollers and hatch cover, the channels being arranged to permit a limited pivoting movement of the hatch cover and rollers in a generally vertical plane when the hatch cover is positioned over the hatch frame at its closed position thereby to provide a clearance between the hatch cover and hatch frame when the hatch cover is moved to open position, and releasable means to secure the hatch cover in closed position.

10. In a hatch cover assembly adapted to be mounted on the roof of a railway hopper car, an elongate hatch cover having a pair of roller arms secured to one side thereof and extending outwardly from said one side, a pair of rollers mounted on each of the arms and being offset from each other, a generally box-shaped channel

adjacent each arm and in alignment with an associated arm for receiving the rollers therein, each box-shaped channel being slotted longitudinally to receive its associated arm, one of the rollers of each pair engaging the bottom of the channel and the other roller engaging the top of the channel for supporting the cover for back and forth movement, and a stop adjacent each end of each channel to limit the movement of the hatch cover.

11. In a railway hopper car, a roof covering the hopper car, an elongate hatch opening extending lengthwise longitudinally of the car, an elongate hatch cover over the hatch opening adapted to move transversely of the car between open and closed positions, a guide on one side of the elongate hatch cover extending outwardly and downwardly from said one side, a fixed guideway for the guide mounted on the roof and extending transversely of the car to support the guide and hatch cover for back and forth movement transversely of the car, said guide comprising an arm secured to the hatch cover and a pair of rollers on the arm offset vertically from each other, said guideway receiving the rollers and having upper and lower surfaces engaging and guiding the movement of the rollers, one of the rollers engaging the upper surface and the other roller engaging the lower surface, the weight of the cover exerting a torque on said arm when supported by the arm and associated rollers for movement back and forth in the guideway, and releasable means to secure the hatch cover in closed position and to release the hatch cover for movement transversely of the car to open position.

12. In a railway hopper car, a roof covering the hopper car and having an elongate hatch opening therein, an elongate hatch cover over the hatch opening and slidable relative to the car between open and closed positions in a direction generally perpendicular to the longitudinal axis of the opening, a pair of spaced generally parallel arms mounted on one side of the elongate hatch cover and extending outwardly and downwardly from said one side, a separate support for each arm secured to the roof and extending transversely of the longitudinal axis of said elongate hatch cover, separate means carried by each arm engaging the associated support at spaced apart positions and mounting the arms and hatch cover for sliding movement along the supports between open and closed positions, the cover being cantilevered by said arms and moving over the supports when moved between closed and open positions, and releasable means to secure the hatch cover in closed position and to release the hatch cover for sliding movement along the supports to open position.
